UNITED STATES PATENT OFFICE.

WILLIAM L. SULLIVAN, OF FERGUSON, MISSOURI.

TICKET-ISSUING MACHINE.

1,145,818.

Specification of Letters Patent.

Patented July 6, 1915.

Application filed October 26, 1914. Serial No. 868,651.

To all whom it may concern:

Be it known that I, WILLIAM L. SULLIVAN, a citizen of the United States, residing at Ferguson, St. Louis county, Missouri, have invented a certain new and useful Improvement in Ticket-Issuing Machines, of which the following is a full, clear, and exact description, such as will enable others skilled in the art to which it appertains to make and use the same.

This invention relates to ticket-issuing machines of the type in which a continuous ticket strip is fed forwardly and severed into lengths containing one or a plurality of tickets, the length of the severed portions of the ticket strip being governed by the operator who actuates a certain key or controlling device when it is desired to issue one ticket, a different key or device when it is desired to issue two tickets, a different key or device when it is desired to issue three tickets, etc.

One object of my present invention is to provide a machine of the character referred to in which the various elements of the machine are operated positively in both directions, thus eliminating various defects that are apt to develop when a spring is employed in a machine of this type for moving the elements of the machine in one direction, either forwardly or to restore them to normal position.

Another object is to provide a machine of the character referred to in which the ticket-strip-feeding mechanism comprises a variable-stroke actuating member that is moved positively in both directions by a driving member having a fixed stroke, means under control of the operator being employed for governing the degree of movement imparted to said variable-stroke-actuating member, so as to control the number of tickets that is issued at each cycle of operations of the machine.

Another object is to provide an electrically-operated ticket-issuing machine which is so designed that when the electric current is cut off the machine is absolutely dead and incapable of issuing a ticket. And still another object is to provide an efficient ticket-issuing machine of simple construction that can be manufactured at a low cost and which comprises fewer parts than the ticket-issuing machines now in general use.

Other objects and desirable features of my invention will be hereinafter pointed out.

Figure 1 of the drawings is a side elevational view of a ticket-issuing machine constructed in accordance with my invention. Fig. 2 is a front elevational view of said machine. Fig. 3 is a vertical transverse-sectional view taken on the line 3—3 of Fig. 1. Fig. 4 is a vertical longitudinal-sectional view taken on the line 4—4 of Fig. 3. Fig. 5 is a top plan view of the machine. Fig. 6 is a horizontal sectional view taken on the line 6—6 of Fig. 3. Fig. 7 is a side-elevational view with one of the side plates of the machine removed, showing the elements of the machine in a different position from the position shown in Fig. 1. Fig. 8 is a vertical transverse-sectional view taken on the line 8—8 of Fig. 7. Fig. 9 is a horizontal-sectional view taken on the line 9—9 of Fig. 7. Fig. 10 is a detail horizontal-sectional view taken on the line 10—10 of Fig. 4. Figs. 11 and 12 are diagrammatic views illustrating slight modifications of my invention.

Briefly described, my invention consists in a ticket-issuing machine that comprises means for feeding a ticket strip forwardly, means for severing said strip into short sections, each of which contains one or a plurality of tickets and means under control of the operator for governing the degree of movement that is imparted to the ticket strip at each cycle of operations of the machine. The elements of the machine are moved positively in both directions, namely, forwardly and back to normal position by a driving member, which is preferably operated by an electric motor, the ticket-strip-feeding mechanism comprising a variable-stroke actuating member that is moved different distances by said driving member. The means under control of the operator which governs the number of tickets that is issued at each cycle of operations of the machine preferably consists of a plurality of key levers or similar devices which coöperate with a means that transmits movement from the driving member to the variable-stroke actuating member of the ticket-strip-feeding mechanism, said coöoperating parts being so designed and arranged that the said actuating member will be moved

different distances, according to which one of the key levers or controlling devices is actuated. In the preferred form of my invention, as herein shown, a switch is provided for controlling the electric current that operates the motor, and means are employed for closing said switch whenever one of the key levers or other controlling devices is actuated and thereafter automatically opening said switch so as to cut off the current after a portion of the ticket strip has been fed forwardly and severed.

Referring to the drawings which illustrate the preferred form of my invention, A designates the counter of a ticket booth underneath which the machine is arranged, the machine being provided with a top plate 1 that is preferably set flush with the top face of the counter A, as shown in Figs. 1 and 2. A continuous ticket strip α that is arranged below the top plate of the machine is fed forwardly through an opening 2 in said top plate by means of a feeding wheel 3 provided with radially projecting pins 4 that enter spaced holes in the ticket strip, the ticket strip passing upwardly over a curved guide plate 5, shown in Fig. 4, that is provided with an elongated slot, through which the pins 4 on the feeding wheel travel. The ticket strip α is prevented from moving off the guide plate 5 by means of a pair of plates 6, shown in Fig. 4, that conform to the curvature of the plate 5, and which coöperate with same to form an arc-shaped guideway for the ticket strip. The plates 6 are preferably carried by a hinged section 1^a of the top plate of the machine, so as to enable said plates to be swung upwardly out of the way when the ticket strip is being engaged with the feeding wheel during the operation of installing the ticket strip in the machine. The ticket strip can either be wound up in the form of a roll and mounted on a supporting shaft or reel, or it can be folded back and forth so as to form numerous parallel portions that lie close together in superimposed relation. I prefer to arrange the ticket strip in the manner just described, as this overcomes the necessity of moving the bulk of the strip each time the strip is fed forwardly, and it also enables the end of a fresh strip to be attached to the strip from which the tickets are being issued before the same is entirely consumed. The ticket strip of the machine herein shown is intended to be folded back and forth and arranged in a box or other suitable container b , shown in broken lines in Figs. 1 and 2, that is retained in an upright position on a stationary support 7 on one of the side plates of the machine by means of a spring clip 8. The feed wheel 3 is rotatably mounted on a stationary shaft or stud 9 carried by one of the side plates 10 of the machine and

by the side wall 11 of the housing in which the feed wheel is arranged, as shown clearly in Figs. 3 and 4. Rotary movement is imparted to the feed wheel 3 by means of a toothed wheel or star wheel 12 on the shaft 70 9 that coöperates with a spring-pressed pawl 13 on the feed wheel, the star wheel 12 being rotated forwardly and backwardly by a positively actuated mechanism, which will be hereinafter described, and thus causing 75 the wheel 3 to move forwardly in the direction indicated by the arrow in Fig. 4, the pawl 13 on the feed wheel snapping over the teeth on the star wheel 12 when said star wheel moves in the reverse direction or opposite to the direction indicated by the arrow in Fig. 4. The mechanism for rotating the star wheel 12 forwardly and backwardly consists of a variable-stroke-actuating member B, herein shown as a vertically 80 reciprocating rack bar that meshes with an idle gear 14, which, in turn, meshes with a gear or pinion 15 on the hub of the star wheel 12, as shown clearly in Figs. 1 and 3, said rack bar or variable-stroke-actuating 85 member B being moved positively in both directions, namely, upwardly and downwardly by a fixed-stroke-driving member C. The driving member C is operated by a rotating part herein shown as a gear D, to which the lower end of the member C is eccentrically connected. It is immaterial, so far as my broad idea is concerned, what the rotating member D consists of, so long as it is a device that moves the driving member 90 95 C positively in two directions and imparts a fixed stroke to same. Instead of using a gear D, as herein shown, I could use a crank shaft provided with a crank arm for operating the driving member C, said crank 100 shaft or rotating element being operated either manually or by some suitable mechanical means. I prefer to operate the rotating member D by means of a motor E, as shown in Figs. 1 and 2, whose shaft is 105 provided with a pinion 16 that meshes with a gear 17 connected to a pinion 18, which, in turn, meshes with the gear D, but it will, of course, be understood that various other means could be employed for connecting the 110 motor to the driving member of the machine without departing from the spirit of my invention.

The machine herein shown is so designed that it will issue one, two, three, four or five tickets, the number of tickets that is issued at each cycle of operations depending upon the degree of movement imparted to the variable-stroke-actuating member B of the ticket-strip-feeding mechanism. The 115 means that I prefer to employ for governing the degree of movement imparted to the member B consists of a plurality of stops arranged in different horizontal planes and mechanism coöperating with said stops and

with the members B and C for causing the driving member C to move the member B variable distances, according to which one of said stops is operative. In the form of my invention shown in Figs. 1 and 7 five stops, 20, 21, 22, 23 and 24 are arranged adjacent the path of movement of a vertically-reciprocating bar 25 that is arranged parallel to the variable-stroke-actuating member 5 or rack bar B, the bar 25 and the bar B being guided by pins 26 or other suitable guiding devices on the side plate 10^a of the machine and having their downward movement limited by suitably arranged stops 26^a.

10 A lever 27 that is pivotally connected to the upper end of the driving member C is joined to the rack bar B and to the bar 25 in such a manner that it will fulcrum first on one of said bars and then on the other bar during the upward stroke of the member C, thereby causing said bars B and 25 to move upwardly, but at different periods, during the upward stroke of the driving member C. The right hand end of the lever 27 is pivotally connected to the bar 25 and the opposite end of said lever 27 is pivotally connected to a link 28 whose lower end is pivotally connected to the rack bar or variable-stroke member B, as shown clearly in Figs. 20 and 7. The pivotal connection between the lever 27 and the fixed-stroke-driving member C is preferably arranged closer to the bar 25 than to the connection between the opposite end of the lever 27 and the link 28 so that the left hand end of the lever 27 will tend to fulcrum on the link 28 as soon as the driving member C starts to move upwardly. In other words, the driving member C is preferably connected to the lever 27 in such a way that there will be no tendency for the variable-stroke member B to start to move upwardly with the member C until the upward movement of the bar 25 is arrested. The function of the stops 20, 21, 22, 23 and 25 is to arrest the upward movement of the bar 25, and in view of the fact that said stops are arranged in different horizontal planes, it will be obvious that the upward movement of the bar 25 will be arrested sooner or later in the upward stroke of the driving member C, according to which of said stops is operative. During the first portion of the upward movement of the driving member C the variable-stroke member B will remain at rest, but the bar 25 will move upwardly with said member C. As soon as the bar 25 has been arrested by one of said stops which was rendered operative when the machine was started, the right-hand end of the lever 27 will fulcrum on the bar 25, and thus cause the variable-stroke member B to move upwardly during the remainder of the upward stroke of the driving member C.

20 From the foregoing it will be seen that the degree of movement imparted to the ticket-strip-feeding mechanism at each cycle of operations of the machine is directly controlled by the stops 20 to 24 which arrest the upward movement of the bar 25 sooner or later in the upward stroke of the driving member C, thereby causing the lever 27 to become operative for transmitting movement from the member C to the member B during the remainder of the upward stroke of the driving member C. The stops 20 to 24, inclusive, in the preferred form of my invention, as herein shown, consist of depending arms of different lengths on key levers 20^a, 21^a, 22^a, 23^a and 24^a that are pivotally mounted on a horizontally disposed shaft 30 arranged underneath the top plate of the machine, said key levers being provided with finger pieces 20^b, 21^b, 22^b, 23^b and 24^b that project upwardly through openings in the top plate 1 of the machine. The depending arms or stops on said key levers are arranged side by side, as shown in Fig. 2, and when said stops are inoperative they lie in the same vertical plane in front of the reciprocating bar 25, as shown in Fig. 1. When one of the key levers is depressed the stop that is controlled by same moves rearwardly into the path of a pawl 31 on the reciprocating bar 25, and when said pawl strikes said stop, as shown in Fig. 7, the upward movement of the bar 25 will be arrested. Thereafter, during the remainder of the upward stroke of the driving member C, the right hand end of the lever 27 will fulcrum on the bar 25 and thus cause the actuating member B to move upwardly until the driving member C reaches the limit of its upward stroke. The pawl 31 is wide enough so that it will engage any of the stops, and, in order to insure a rigid structure, I have pivotally mounted the pawl 31 between the bar 25 and a short bar 25^a, arranged parallel to the bar 25 and connected to same by horizontally disposed pins 25^b, thus producing a rectangular-shaped frame on one side of the bar 25 in which the pawl 31 is pivotally mounted. The pawl 31 is pivotally connected at its lower end to this frame so that gravity tends to move the upper end of the pawl forwardly or into such a position that it will strike the stop that has been rendered operative by depressing the key lever which corresponds to the number of tickets that it is desired to issue, and, in order to eliminate the possibility of the pawl 31 assuming an inoperative position, I have provided said pawl with a pin 31^a that strikes a stationary stud 31^b, shown in Fig. 7, in case the upper end of the pawl is not swung forwardly by the time the bar 25 reaches the limit of its downward stroke. The means for limiting the forward movement of the pawl 31 so that there is not liability of the same engaging any stop except the one that is operative, preferably 10

110 115 120 125 130

consists of a vertically disposed stationary plate 31^c that lies adjacent the path of movement of the member 25, said pawl being adapted to slidably engage the rear edge of said plate, as shown in Fig. 7.

As previously stated, the key levers are pivotally mounted on a stationary horizontally disposed shaft 30, said key levers being spaced apart by means of washers or spacing devices 32. In order to eliminate the possibility of one key lever moving accidentally when the key lever adjacent thereto is actuated, I have provided means for preventing the spacing devices 32 from turning 10 or moving in such a manner that they would serve to frictionally connect two adjacent key levers together, said means consisting of a stationary pin 33, shown in Fig. 7, that passes transversely through all of the 15 spacing devices 32, and thus prevents said devices from moving with the key levers. The depending arms on the key levers that constitute the stops 20 to 24, inclusive, have spacing strips 34 arranged between same, 20 as shown clearly in Fig. 9, and means are provided for causing said spacing strips to exert sufficient frictional pressure on said stops to prevent them from accidentally moving forwardly into an inoperative position 25 after they have been rendered operative. As shown in Figs. 7 and 9, the spacing strips 34 are loosely mounted on two stationary guiding pins 35 on one of the side plates of the machine, and a spring 36 supported by one of said guide pins, is interposed between the other side plate of the machine and the outer spacing strip 34. The frictional pressure that the spacing strips exert on the stops, due to the pressure 30 of the spring 36, causes the stops to remain in an operative position or rearward position after they have been set up or rendered operative by manipulating the key levers. A bar 37 that extends transversely under the 35 key levers, as shown in Fig. 7, forms a stop that limits the downward movement of the key levers, said bar 37 being supported by screws or other suitable fastening devices 38 that are connected to a horizontally disposed plate 1^b which is spaced away from the underside of the top plate 1 of the machine. The key levers 20^a to 24^a, inclusive, are moved positively back to normal position 40 by means of a cam 39 on the hub of the pinion 15 of the ticket-strip-feeding mechanism that cooperates with a pawl or dog 40 carried by a shaft 41 arranged at the rear of the depending arms or stops on the key levers and extending transversely across 45 same. The shaft 41 is supported by two links 42 which are pivotally mounted on the key lever shaft 30, and when any one of the key levers is depressed, this shaft 41 is moved rearwardly into the position shown in Fig. 7. During the first portion of the

forward stroke of the ticket-feeding mechanism the pawl 40 on said shaft merely swings upwardly when the free end of same is acted upon by the cam 39, said pawl being held in the path of movement of said cam by means of a spring 43, shown in Figs. 1 and 7. During the reverse stroke of the ticket-strip-feeding mechanism the cam 39, which is then traveling in a clock-wise direction, or to the right, exerts pressure on the free end of the pawl 40 and moves said pawl to the right, looking at Fig. 7, thereby causing the shaft 41 to engage the stop which is then operative and move said stop back to its normal position.

From the foregoing it will be seen that the key levers or controlling devices which govern the number of tickets issued are frictionally held in operative position and are moved positively back to normal position prior to the completion of the cycle of operations of the machine.

The feed wheel 3 is prevented from moving backwardly by means of a spring-pressed pawl 45, shown in Fig. 4, that cooperates with the pins 4 on said wheel, and means are provided for preventing said feed wheel from jumping forwardly suddenly when the mechanism that imparts forward movement to said wheel starts to operate, the means herein shown for accomplishing this consisting of a friction plate 46 carried by the side wall 11 of the feed wheel housing and arranged in such a manner that it will bear upon one side of a gear 47 that is connected to the hub 3^a of the feed wheel, as shown clearly in Figs. 3, 4, and 10, said friction plate 46 being under the influence of an adjustable coil spring 48 shown in Figs. 3 and 10 that causes said plate to exert pressure on the gear 47. This gear 47 forms part of the counting mechanism that records the number of tickets issued from the machine, and in the preferred form of my invention, as herein shown, the gear 47 meshes with an idler 49 that drives a pinion 49^a that operates the counting wheels 50 of the recording mechanism which are exposed to view through an opening in the top plate of the machine, as shown in Figs. 4 and 5. By providing a brake or friction device for preventing the feeding wheel from jumping forwardly suddenly I eliminate the possibility of the pawl 13 on the feeding wheel becoming accidentally disengaged from the proper tooth of the star wheel 12, or, in other words, from jumping forward one tooth of the star wheel. Means are also provided for preventing the feed wheel 3 from overthrowing, and in the machine herein shown said means consists of a stop or abutment member 51 that is moved into the path of travel of the spokes of the feed wheel 3 just before said feed wheel completes its forward stroke, during the operation of feeding the ticket-

115

120

125

strip forwardly. The stop or abutment member 51 is arranged horizontally in a guiding sleeve 52 on one of the side plates of the machine, as shown in Fig. 8, and the 5 outer end of said stop is pivotally connected to a lever 53 whose lower end is pivotally connected at 54 to a bracket 55 on said side plate, as shown in Figs. 7 and 8. A coil spring 56 that is connected to a laterally 10 projecting arm on the lever 53, as shown in Fig. 7, moves said lever in one direction, preferably into such a position that the stop 51 will extend into the path of movement of the spokes of the feed wheel, and a bar 57 15 that is pivotally connected to the upper end of the driving member C moves said lever 53 in the opposite direction, namely, to withdraw the stop 51 from the path of the spokes of the feed wheel 3. As shown in Fig. 7, the 20 bar 57 is provided with a notch or cut-out portion 57^a that comes into alignment with a roller 58 on the lever 53 just before the feed wheel 3 completes its forward stroke, thus permitting the spring 56 to move the lever 25 53 forwardly or into the position shown in Fig. 8. On the return stroke of the driving member C the notch or cut-out portion in the bar 57 moves out of alignment with the roller 58, thus causing said roller to ride up 30 onto a solid portion of the bar 57, and consequently, acting to move the lever 53 outwardly or into such a position that the stop or abutment member 51 will not be engaged by the spokes of the feed wheel during the 35 first part of the succeeding forward stroke of the feed wheel.

The severing mechanism for dividing the ticket strip into sections consists of a stationary cutter 60 arranged horizontally at 40 one side of the ticket-strip opening 2 in the top plate of the machine and a co-operating movable cutter 61 arranged above the stationary cutter and pivotally connected at one end of same. The stationary cutter is 45 detachably connected by means of screws 60^a to the plate 1^b that is arranged under the top plate of the machine, and the movable cutter is pivotally connected to said stationary cutter by means of a pin 62, shown in 50 Fig. 3, that projects downwardly through an opening in the stationary cutter. A spring 63 that is interposed between a head on the pin 62 and the underside of the stationary cutter operates to draw the movable cutter downwardly against the stationary cutter, thereby preventing the movable cutter from springing away from the stationary cutter. The movable cutter 61 is operated 55 positively in both directions by means of a rock arm 64 that is provided at its upper end with a hook-shaped device 65 that embraces the free end of the movable cutter, as shown clearly in Figs. 6 and 7. The rock arm 64 is loosely mounted on the stationary 60 shaft 9 which supports the ticket-strip feed

wheel, and in the preferred form of my invention as herein shown, said rock arm is provided with an angularly disposed extension 66, shown in Fig. 7, which is connected by means of a link 67 with the motor-driven element D of the machine. The link 67 is, of course, eccentrically connected to the rotating element D so that said link will be reciprocated upwardly and downwardly once at each cycle of operations of the machine. 70 In the machine herein shown an angularly disposed crank arm 68, which is rigidly connected to the pin that secures the driving member C to the gear D, is provided at its free end with a pin or stud 69 that projects 80 into an elongated slot 67^a in the link 67, as shown in Fig. 7. At each complete cycle of the gear D the crank arm 68 moves the link 67 upwardly and downwardly once, thus causing the movable cutter 61 to be positively closed and thereafter positively opened or restored to normal position. 85

In order to eliminate the possibility of the cutter-operating rock arm 64 moving accidentally when the pin 69 on the crank arm is traveling from one end to the other of the elongated slot in the link 67, I have provided a spring 70 that is connected at one end to the rock arm 64 and at its opposite end to a stationary part of the frame of 95 the machine, so as to exert sufficient pressure on said rock arm to prevent it and the link 67 from being moved by the frictional contact of the crank pin 69 on the side walls of the elongated slot in the link 67. 100

As previously stated, a switch is employed for controlling the electric current that operates the motor E, and means are provided for closing said switch when any one of the key levers is depressed and for thereafter automatically opening said switch so as to 105 cut off the electric current. Any suitable type of switch may be employed, and various means may be used for operating said switch. In the machine herein shown the 110 switch comprises two spring contact fingers 71, shown in Fig. 1, arranged in the electric circuit y that operates the motor, and a movable or shiftable member 72 that establishes electrical connection between the 115 spring contact fingers 71 when said member 72 is in a certain position. The movable element 72 of the switch is connected to a block of insulating material 73 which normally occupies such a position that the free 120 ends of the spring contact fingers 71 bear upon same, as shown in Figs. 1, 2 and 3. When one of the key levers of the machine is depressed the insulating block 73 is moved upwardly far enough to bring the conducting member 72 on said block into engagement with the spring contact fingers 71, thus closing the circuit y. The means that I prefer to use for raising and lowering the insulating block 73 so as to close and open 130

the switch consists of a rearwardly projecting arm 42^a on one of the links 42 that is pivotally connected at its outer end to a vertically disposed bar 74 that carries the 5 insulating block 73, said bar 74 being guided by stationary guide pins 75 or other suitable guiding devices. When the transversely disposed shaft 41, previously described, is moved rearwardly by the stop on the key 10 lever which is operated, the arm 42^a moves upwardly and thus shifts the movable element of the switch into its closed or operative position. When said shaft 41 is moved forwardly by the cam 39, previously de- 15 scribed, which co-operates with the dog 40 on said shaft, the arm 42^a moves downwardly and thus opens the switch.

While I prefer to employ means of the character illustrated in Figs. 1 and 7 for 20 transmitting movement from the driving member of the machine to the variable-stroke-actuating member of the ticket-issuing mechanism, I wish it to be understood that my invention is not limited to a means 25 of this character, for my broad idea consists in a connection between the driving member and said variable-stroke-actuating member and means under control of the operator that co-operates with said connection 30 for causing said driving member to move the actuating member variable distances.

In Fig. 11 I have illustrated a slight modification of my invention wherein a toothed rockable member 27^a is employed for connecting the driving member C to the bar 25 and to the variable-stroke-actuating member B. The upper end of the driving member is pivotally connected to the rockable member 27^a, and said member is provided with two 40 segmental-shaped racks, preferably of different arcs, that mesh with rack teeth on the bar 25 and on the actuating member B. When the driving member C starts to move upwardly the member 27^a will rock on the 45 bar B until the upward movement of the bar 25 is arrested by the stop which the operator of the machine set up or rendered operative. Thereafter the member 27^a will rock in the 50 opposite direction, fulcruming on the bar 25, and thus causing the actuating member B to move upwardly during the remainder of the upward stroke of the driving member C.

In the form of my invention shown in 55 Fig. 12 the variable-stroke-actuating member B' of the ticket-issuing mechanism is provided with five stops 80 arranged in different horizontal planes and each controlled by one of the key levers of the machine. The key levers are provided with depending 60 arms or extensions that are arranged in such a position with relation to the stops 80 that any of said stops can be shifted into the path of movement of a pawl 81 on the driving member C' of the machine. When the driv-

ing member C' moves upwardly the variable-stroke-actuating member B' will remain at rest until the pawl on said driving member engages the stop 80 on the actuating member which is then operative. Thereafter the actuating member B' will move upwardly 70 with the driving member. On the return stroke of the driving member a pin or other suitable device 82 on said member engages a pin or other suitable device 83 on the actuating member B' and moves said actuating member 75 downwardly, so as to restore the ticket-strip-feeding mechanism to normal position. When the machine is idle the electric current is cut off and it is absolutely impossible to issue a ticket from the machine by depressing one of the key levers, owing to the fact that the various elements of the machine are operated positively in both directions, namely, forwardly and back to starting position. Furthermore, when the machine is 85 idle it is not in condition for issuing either one or a certain number of tickets, it being necessary to depress one of the key levers or operate one of the key levers or ticket-controlling devices each time it is desired to 90 issue a ticket from the machine.

If the operator desires to issue two tickets the key lever 21^a is depressed so as to move the stop 21 rearwardly or into operative position, as shown in Fig. 7, the depression of said key lever causing the switch that controls the circuit y to close. When the motor E starts to operate, the bar 25 will move upwardly with the actuating member C until the pawl 31 on said bar strikes the 100 operative stop 21, the variable-stroke-actuating member B remaining at rest up to this point. After the upward movement of the bar 25 has been arrested by the operative 105 stop 21, the lever 27 will fulcrum on the bar 25, and will thus cause the actuating member B to move upwardly during the remainder of the upward stroke of the driving member C, thus causing the feed wheel 3 to move the ticket-strip α forwardly far enough 110 to feed two tickets past the severing mechanism. On the reverse stroke of the driving member C the actuating member B and the bar 25 are both moved downwardly positively and are thus positively restored to 115 starting position prior to the completion of the cycle of operations of the machine. The movable cutter 61 of the severing mechanism is closed positively after the forward movement of the ticket-strip ceases, and after the ticket strip has been severed said cutter is moved positively in the opposite direction, or back to its normal open position. On the reverse or downward stroke of the driving member C the stop 21 and key lever 21^a are 120 moved positively back to their normal positions by means of the cam 39 acting on the pawl or dog 40 that is connected to the shaft 125.

41 which extends transversely across the controlling stops. If it is desired to issue five tickets the operator depresses the key lever 24^a so as to move the stop 24 into operative position, said stop being so located that it will arrest the upward movement of the bar 25 at practically the beginning of the upward stroke of the driving member C, thus causing the actuating member B to 5 move upwardly throughout practically the entire upward stroke of said driving member. There is no danger of the ticket-strip feed wheel jumping forwardly suddenly when it starts to move, owing to the fact 10 that the brake plate 46 exerts frictional pressure on the feed wheel, or rather on a part connected with the feed wheel, and consequently there is no danger of the pawl 13 on the feed wheel jumping forwardly one tooth 15 20 on the star wheel 12, nor is there any danger of the feed wheel overthrowing, in view of the fact that the stop 51 moves into the path of the spokes on the feed wheel just prior to the completion of the forward movement of 25 said feed wheel. The spring-pressed spacing strips that are arranged between the controlling stops insure said stops and the key levers remaining in operative position. As said parts are restored positively to normal 30 position, there is no liability of one of the stops or key levers sticking, as might occur if springs were employed for restoring the key levers and controlling stops, nor is there any liability of the movable cutter of 35 the severing mechanism sticking in either its closed or open position, in view of the fact that said cutter is moved positively in both directions.

All of the parts of the machine are accessible either for adjustment or repairs, and as the machine comprises only a few parts, all of which are of simple construction, the machine can be manufactured cheaply and there is very little liability of its getting 40 out of order when it is in use. The machine is compact and takes up but little space when it is installed, and if desired, it can be equipped with a driving pinion 85, meshing with the gear D, as shown in dotted lines in 45 Fig. 7, for imparting movement to a shaft that is employed for driving a number of machines, thus enabling a single motor to be used for operating a plurality of machines, each of which is, of course, equipped with a 50 separate switch for controlling the electric circuit that energizes the motor.

Having thus described my invention, what I claim and desire to secure by Letters Patent is:

60 1. A ticket-issuing machine provided with a positively acting driving means for moving the various elements of the machine forwardly and also backwardly to restore them to starting position.

2. A ticket-issuing machine provided with

a motor-operated driving element which positively moves the various elements of the machine forwardly to cause the machine to operate and also backwardly to restore said elements to starting position.

3. A ticket-issuing machine provided with a ticket-strip-feeding mechanism, and a positively-acting driving means for moving certain elements of said mechanism forwardly to cause said mechanism to operate and for moving said elements backwardly to restore them to starting position.

4. A ticket-issuing machine provided with a ticket-strip-feeding mechanism that comprises a part which moves forwardly and backwardly, and a motor-driven element which positively actuates said part forwardly and backwardly at each cycle of operations of the machine.

5. A ticket-issuing machine provided with a ticket-strip-feeding mechanism that comprises an actuating member which causes the ticket strip to be fed forwardly when said member moves in one direction, and a driving member for moving said actuating member positively in both directions.

6. A ticket-issuing machine provided with a ticket-strip-feeding mechanism that comprises an actuating member which causes the ticket strip to be fed forwardly when said member moves in one direction, and a motor-driven element which moves said actuating member forwardly and backwardly.

7. A ticket-issuing machine comprising a ticket-strip-feeding mechanism and a severing mechanism for dividing said ticket strip into sections, and a positively-acting driving means that operates said mechanisms forwardly and backwardly so as to cause them to operate and then be restored to starting position at each cycle of operations of the machine.

8. A ticket-issuing machine comprising a ticket-strip-feeding mechanism and a severing mechanism for dividing said ticket-strip into sections, and a motor-operated driving means that positively actuates said mechanisms in both directions, namely, on their forward and on their return strokes.

9. An actuating mechanism, comprising a variable-stroke member, a driving member having a fixed stroke in both directions, a connection between said members for transmitting movement from said driving member to said variable-stroke member, and means co-operating with said connection for determining the degree of movement imparted to said variable-stroke member.

10. An actuating mechanism, comprising a fixed-stroke driving member, a variable-stroke driven member, a connecting element interposed between said members for transmitting movement from the driving member to the driven member, and a plurality of controlling devices that are adapted to co-

operate with said connecting element for governing the degree of movement imparted to said variable-stroke member.

11. A ticket-issuing machine provided with a variable-stroke-ticket-strip-feeding mechanism and a fixed stroke driving means for actuating said feeding mechanism forwardly and in the reverse direction.

12. A ticket-issuing machine provided with a ticket-strip-feeding mechanism, a positively acting driving means for operating said feeding mechanism forwardly and in the reverse direction, and means for governing the degree of movement which said driving means imparts to said feeding mechanism on its forward stroke.

13. A ticket-issuing machine provided with a ticket-issuing mechanism, a driving means for positively operating said mechanism forwardly and restoring it, and means under control of the operator coöperating with said issuing mechanism for causing one or a plurality of tickets to be issued at each cycle of operations of the machine.

14. A ticket-issuing machine provided with a ticket-issuing mechanism, a driving means for positively operating said mechanism forwardly and restoring it, and a plurality of devices under control of the operator for governing the degree of movement which said driving means imparts to said issuing mechanism on the forward stroke of said mechanism, thereby enabling the number of tickets that is issued at each cycle of operations of the machine to be varied at the will of the operator.

15. A ticket-issuing machine provided with a ticket-issuing mechanism, a driving means for positively operating said mechanism forwardly and restoring it, and a plurality of manually-operated controlling devices coöperating with said issuing mechanism and driving means and each of which is adapted to cause the ticket-issuing mechanism to have a different degree of movement imparted to same on the forward stroke of said driving means.

16. A ticket-issuing machine comprising a ticket-issuing mechanism, a driving element for actuating said mechanism and restoring it, a motor of any suitable kind for operating said driving element, means under control of the operator coöperating with said issuing mechanism for determining the number of tickets that is issued at each cycle of operations of the machine, and means for causing said motor to become operative whenever said ticket-controlling means is actuated.

17. A ticket-issuing machine comprising a ticket-issuing mechanism, a driving element for actuating said mechanism and restoring it, a motor of any suitable kind for operating said driving element, means under control of the operator coöperating with

said issuing mechanism for determining the number of tickets that is issued at each cycle of operations of the machine, and a controlling device for the medium that operates said motor which is rendered operative whenever said ticket-controlling means is actuated.

18. A ticket-issuing machine comprising a ticket-issuing mechanism, a driving element for actuating said mechanism and restoring it, an electric motor for operating said driving element, means under control of the operator coöperating with said issuing mechanism for causing one or a plurality of tickets to be issued at each cycle of operations of the machine, and means for causing said motor to start to operate whenever said controlling means is actuated and cease operating after the parts of the machine have been restored to starting position.

19. A ticket-issuing machine comprising a ticket-issuing mechanism, a driving element for actuating said mechanism and restoring it, an electric motor for operating said driving element, means under control of the operator coöperating with said issuing mechanism for causing one or a plurality of tickets to be issued at each cycle of operations of the machine, a switch for controlling the electric current that operates the electric motor, and means coöperating with said ticket-controlling means for closing said switch when said ticket-controlling means is actuated and for thereafter automatically opening said switch prior to the completion of the cycle of operations of the machine.

20. A ticket-issuing machine comprising a ticket-issuing mechanism, a driving element for actuating said mechanism and restoring it, an electric motor for operating said driving element, a plurality of manually-operated controlling devices for governing the number of tickets issued at each cycle of operations of the machine, a switch for governing the motor, and means governed by said ticket-controlling devices for closing said switch and causing it to remain closed up to a certain period in the cycle of operations of the machine.

21. A ticket-issuing machine comprising a ticket-issuing mechanism, a driving element for actuating said mechanism and restoring it, an electric motor for operating said driving element, a plurality of manually-operated controlling devices for governing the number of tickets issued at each cycle of operations of the machine, a switch for governing the motor, means governed by said ticket-controlling devices for closing said switch when any of said devices are actuated, and means for opening said switch after the elements of the machine have been restored to starting position.

22. A ticket-issuing machine comprising a ticket-issuing mechanism, a driving element for actuating said mechanism and restoring it, an electric motor for operating said driving element, a plurality of manually-operated controlling devices for determining the number of tickets that is issued at each cycle of operations of the machine, a switch for governing the motor, and means for opening and closing said switch, said switch-actuating means being moved in the direction to close the switch when one or the other of said ticket-controlling devices is actuated. 5
23. A ticket-issuing machine provided with a variable-stroke ticket-strip-feeding mechanism that comprises a reciprocating member, a movable cutter for severing said strip into sections, a rotating element, and mechanism operated by said rotating element for opening and closing said movable cutter and for moving said reciprocating member back and forth. 10
24. A ticket-issuing machine comprising a variable-stroke ticket-strip-feeding mechanism, a movable cutter for severing said strip into sections, a rotating element, means operated by said rotating element for opening and closing said movable cutter, said means being so designed that the movable cutter remains at rest during part of the cycle of operations of said rotating element, an independent means operated by said rotating element for actuating said feeding mechanism, and mechanism under control of the operator for causing said feeding mechanism to operate and for determining the degree of movement said feeding mechanism will impart to the ticket strip. 15
25. A ticket-issuing machine provided with a ticket-strip-feeding mechanism that comprises a reciprocating member, a movable cutter for severing said strip into sections, a rotating element, means operated by said rotating element for opening and closing said movable cutter, said means being so designed that the movable cutter remains at rest during part of the cycle of operations of said rotating element, means for preventing said movable cutter from moving accidentally during the period when it is not being actuated by said rotating element, and an independent means actuated by said rotating element for positively moving said reciprocating member in both directions. 20
26. An actuating mechanism, comprising a driving member having a fixed stroke in both directions, a reciprocating variable-stroke member, means for transmitting movement from said driving member to said variable-stroke member, and a plurality of devices that cooperate with said means for determining the degree of movement imparted to said variable-stroke member. 25
27. A ticket-issuing machine provided with a ticket-strip mechanism, a movable cutter for severing said strip into sections, a rock arm for actuating said cutter, a rotating element, a link eccentrically connected to said element and fastened to said rock arm for positively opening and closing said movable cutter, said link having an elongated slot for receiving a device which connects it to said rotating element, and a spring connected to said rock arm and to a stationary part of the machine for holding said rock arm at rest while said connecting device is traveling from one end to the other of the elongated slot in said link. 30
28. A ticket-issuing machine provided with a ticket-strip-feeding mechanism, a severing mechanism comprising a stationary cutter and a movable cutter arranged on opposite sides of the ticket-strip, a pin on said movable cutter that pivotally connects same to said stationary cutter, a coiled spring arranged between said stationary cutter and a head on said pivot pin which tends to prevent the movable cutter from springing away from the stationary cutter during the operation of severing the strip, and means for positively moving said movable cutter in both directions to open and close same. 35
29. A ticket-issuing machine comprising manually-operated devices for controlling the issuance of tickets, a restoring mechanism for said devices that is rendered operable when one of said devices is actuated, and a movable element which actuates said restoring mechanism when the other parts of the machine are moved back to starting position. 40
30. A ticket-issuing machine comprising controlling devices for governing the issuance of tickets, a restoring mechanism for said controlling devices that is rendered operable when one of said devices is actuated, and a movable element co-operating with said restoring mechanism and arranged in such a manner that it operates said restoring mechanism only when the machine is completing its cycle of operations. 45
31. A ticket-issuing machine provided with a ticket-strip-feeding mechanism that comprises an actuating member which is moved positively on its forward and return strokes, manually-operated controlling devices for governing the number of tickets that is issued, a restoring mechanism for said devices that is rendered operable when one of said devices is actuated, and means operated by said actuating member for causing said restoring mechanism to return the ticket-controlling devices to normal position. 50
32. A ticket-issuing machine provided with a ticket-strip-feeding mechanism that comprises an actuating member which is moved positively on its forward and return strokes, manually-operated controlling devices for governing the number of tickets 55

that is issued, a restoring mechanism for said devices that is rendered operable when one of said devices is actuated, a rotating element that is actuated forwardly and backwardly by said actuating member, and a device forming part of said restoring mechanism that travels freely over said rotating element when said element is moving in one direction, but which is moved positively by 10 said element when it rotates in the opposite direction.

33. A ticket-issuing machine comprising a ticket-strip-feeding mechanism, manually-operated controlling devices for governing 15 the number of tickets that is issued, a restoring mechanism for said devices that is moved in one direction when any of said devices is operated, said restoring mechanism comprising a pawl, and a rotating element 20 operated by the ticket-strip-feeding mechanism and arranged to engage said pawl and move the restoring mechanism in the opposite direction prior to the completion of the cycle of operations of the machine.

34. A ticket-issuing machine comprising a ticket-strip feeding mechanism, pivotally mounted key levers for controlling the number of tickets that is issued, arms on said key levers, a swinging bar arranged transversely 30 of said arms in such a position that it will be moved in one direction when any of the key levers is depressed, a cam that is moved forwardly and backwardly by said ticket-strip-feeding mechanism, and a spring-pressed pawl on said bar that co-operates 35 with said cam for causing said bar to restore the key levers to normal position.

35. A ticket-issuing machine provided 40 with manually-operated controlling devices for governing the number of tickets that is issued, and a friction means for preventing any one of said devices that has been rendered operative from accidentally returning to normal position.

36. A ticket-issuing machine provided 45 with manually-operated controlling devices for governing the number of tickets that is issued, and a friction means that always exerts pressure on said devices and thus holds 50 said devices in both their operative and inoperative positions.

37. A ticket-issuing machine comprising 55 controlling devices for governing the issuance of tickets, and means for holding said devices in an operative position consisting of members that exert frictional pressure on said devices.

38. A ticket-issuing machine provided 60 with manually-operated ticket-controlling devices that comprise parts which lie side by side, spacing members interposed between said parts, and means for causing said spacing members to exert frictional pressure on said parts.

39. A ticket-issuing machine comprising 65 a plurality of manually-operated controlling devices that comprise parts which lie side by side, spacing strips interposed between said parts, and resilient means for causing said spacing strips to exert pressure on said 70 parts.

40. A ticket-issuing machine provided 75 with a plurality of controlling key levers which have depending arms that lie side by side, and members interposed between said arms that exert sufficient frictional pressure on same to hold the key levers in either their elevated or depressed positions.

41. A ticket-issuing machine provided 80 with a plurality of pivotally mounted key levers having arms or extensions that lie side by side, spacing strips interposed between said arms and movably mounted on a stationary guiding device, and a resilient means for causing said spacing strips to exert frictional pressure on said arms.

42. In a machine of the character described, a forwardly-rotating feed wheel, means for moving said feed wheel intermittently, a disk-shaped part arranged to move 90 with the feed wheel, a stationary support arranged adjacent said disk-shaped part, and a spring-pressed device on said support that exerts pressure on one side of said disk-shaped part and thus prevents said wheel from jumping forwardly suddenly when it is actuated.

43. In a machine of the character described, means for rotating the feed wheel 100 forwardly intermittently, a disk-shaped part joined to the feed wheel and arranged parallel to same, and a frictional brake that bears against the side of said disk-shaped part and thus prevents said feed wheel from jumping forwardly suddenly when it is actuated.

44. A ticket-issuing machine comprising 103 a ticket-strip-feed wheel provided with a pawl, an oscillating star wheel that co-operates with said pawl to move said feed wheel forwardly intermittently, and a spring-actuated brake for exerting frictional pressure on a part connected with the feed wheel so as to prevent said wheel from moving too freely.

45. In a ticket-issuing machine, an intermittently-operating feed wheel, a gear wheel 110 connected to said feed wheel for actuating one part of the machine, and a frictional brake co-operating with said gear wheel for preventing said wheel from moving forwardly too freely.

46. A ticket-issuing machine provided 115 with a ticket-strip-feed wheel, an operating mechanism for said wheel comprising a positively-actuated driving member, a stop for preventing said feed wheel from overthrowing, and means governed by said driving

member for permitting said stop to become operative just prior to the completion of the forward stroke of the feed wheel.

47. A ticket-issuing machine comprising 5 a ticket-strip-feed wheel, a stop for preventing said wheel from overthrowing, means for causing said stop to become operative just prior to the completion of the forward stroke of the feed wheel, and means 10 for rendering said stop inoperative prior to the succeeding forward stroke of the feed wheel.

48. A ticket-issuing machine provided with 15 a feed wheel, a spring-actuated device for preventing said feed wheel from overthrowing, and a positively-operated member having a fixed stroke in both directions for permitting said device to become operative and for rendering said device inoperative.

20 49. A ticket-issuing machine provided with a ticket-strip-feed wheel, a stop for preventing said feed wheel from overthrowing, a lever for actuating said stop for moving said lever in one direction, and a positively- 25 operated member having a fixed stroke for moving said lever in the opposite direction.

50. A ticket-issuing machine provided 30 with a ticket-strip-feed wheel, a stop for preventing said feed wheel from overthrowing, a lever for actuating said stop, a spring for moving said lever in one direction, a positively-operated member having a fixed 35 stroke for moving said lever in the opposite direction, a device on said lever which normally bears upon said positively-operated member, and a notch or cutout portion in said member that comes into alignment with said device and thus permits the spring to move said lever in one direction when said 40 member reaches a certain position.

51. A ticket-issuing machine provided 45 with a ticket-issuing mechanism that comprises a variable-stroke-actuating member, a positively-operated driving member having a fixed stroke in both directions, a connection 50 between said members, and means under control of the operator that co-operates with said connection for governing the degree of movement imparted to said variable-stroke member on the forward stroke of the driving member.

52. A ticket-issuing machine provided 55 with a ticket-issuing mechanism that comprises a variable-stroke-actuating member, a driving member having a fixed stroke, and means under control of the operator for causing said actuating member to be moved sooner or later on the forward stroke of said driving member, depending upon the number 60 of tickets that it is desired to issue.

53. A ticket-issuing machine provided 65 with a ticket-issuing mechanism comprising a variable-stroke-actuating member, a fixed-stroke driving member, a connection be-

tween said members which is so designed 65 that the variable-stroke-actuating member is capable of remaining at rest during the forward stroke of the driving member, and a plurality of governing devices, each of which is under control of the operator for 70 causing said actuating member to be moved by said driving member at different periods on the forward stroke of said driving member.

54. A ticket-issuing machine provided 75 with a ticket-issuing mechanism comprising a variable-stroke-actuating member, a fixed-stroke driving member, a connection between said members which is so designed that the variable-stroke-actuating member 80 is capable of remaining at rest during the forward stroke of the driving member, and a plurality of governing devices under control of the operator for causing the driving member to move the actuating member different 85 distances on the forward stroke of said driving member.

55. A ticket-issuing machine provided 90 with a ticket-issuing mechanism that comprises a variable-stroke-actuating member, a driving member that has a fixed stroke in both directions, means interposed between said members for transmitting movement from said driving member to said actuating member, both on the forward and return 95 strokes of said driving member, and a plurality of devices under control of the operator that co-operate with said means for determining the degree of movement that is imparted to said actuating member on its 100 forward stroke.

56. In a ticket-issuing machine, a ticket-issuing mechanism comprising a variable-stroke-member, a driving member having a fixed stroke in both directions, a plurality 105 of controlling stops governed by the operator and arranged in different positions, and means connected to the driving member which is inoperative for transmitting movement to said actuating member until after 110 it has engaged the stop that is then operative.

57. A ticket-issuing machine provided 115 with a ticket-issuing mechanism that comprises a variable-stroke-actuating member, a driving member having a fixed stroke, a reciprocating bar arranged parallel to said actuating member, a connection between said driving member and said bar and actuating member which is so designed that said bar 120 will start to move on the forward stroke of the driving member, and means under control of the operator for arresting the forward movement of said bar in different positions so as to cause said connection to thereafter transmit movement from the driving member to said actuating member.

58. A ticket-issuing machine provided

with a ticket-issuing mechanism that comprises a variable-stroke-actuating member, a driving member having a fixed stroke, a reciprocating bar arranged parallel to said actuating member, a connection between said driving member and said bar and actuating member which is so designed that said bar will start to move on the forward stroke of the driving member, and a plurality of devices under control of the operator, each of which will arrest the movement of said bar at a different period in the forward stroke of the driving member, thus causing said connection to transmit movement to the actuating member during the remainder of the forward stroke of said driving member.

59. A ticket-issuing machine provided with a ticket-issuing mechanism that comprises a variable-stroke-actuating member, a driving member having a fixed stroke, a reciprocating bar arranged parallel to said actuating member, a connection between said driving member and said bar and actuating member which is so designed that said bar will start to move on the forward stroke of the driving member, a plurality of stops under control of the operator that are arranged in different horizontal planes, and a device on said bar for engaging the stop that is operative so as to arrest the movement of said bar and thus cause said connection to transmit movement to the actuating member during the remainder of the forward stroke of the driving member.

60. A ticket-issuing machine provided with a ticket-strip-feeding mechanism that comprises a reciprocating actuating member, a positively-operated driving member, a reciprocating bar arranged parallel to said actuating member, a rockable device pivotally connected to said driving member and engaged with said actuating member, and reciprocating bar for transmitting movement to said elements from the driving member, a plurality of stops arranged adjacent the path of movement of said reciprocating bar and located in different horizontal planes, and a pawl on said bar that is adapted to coöperate with said stops for controlling the degree of movement imparted to said actuating member.

61. A ticket-issuing machine having a ticket-strip-feeding mechanism that comprises a reciprocating actuating member, a reciprocating bar arranged parallel to said member, a rockable element arranged between said bar and actuating member and engaged with same, a positively-actuated driving member pivotally connected to said rockable element, and means for arresting the forward movement of said reciprocating bar and holding it at rest at different periods in the forward stroke of said driving member, thereby causing said rockable element

to move said actuating member different distances.

62. A ticket-issuing machine having a ticket-strip-feeding mechanism that comprises a reciprocating actuating member, a reciprocating bar arranged parallel to said member, a rockable element arranged intermediate said bar and actuating member and engaged with same, a driving member connected to said rockable element in such a manner that said bar will start to move on the forward stroke of said driving member, and a plurality of manually-controlled devices arranged in different horizontal planes for arresting the forward movement of said reciprocating bar at different periods in the forward stroke of said driving member.

63. A ticket-issuing machine having a ticket-strip-feeding mechanism that comprises an actuating member, a reciprocating bar arranged parallel to said actuating member, a plurality of key levers provided with depending arms of different lengths, a pawl on said reciprocating bar that is adapted to coöperate with the arm of a lever that has been actuated, and a positively-actuated driving member connected to said bar and actuating member in such a manner that the actuating member will start to move forwardly after the pawl on said bar has engaged the arm on one of said key levers.

64. A ticket-issuing machine provided with a ticket-strip-feeding mechanism that comprises a reciprocating actuating member, and operating means for said actuating member comprising a reciprocating bar and a plurality of key levers provided with depending arms of different lengths that constitute stops which limit the forward movement of said reciprocating bar and thus control the degree of movement imparted to said actuating member.

65. In a ticket-issuing machine, a plurality of key levers provided with depending arms of different lengths that normally lie side by side in the same vertical plane, a ticket-strip-feeding mechanism comprising an actuating member and operating means for said actuating member comprising a reciprocating bar, and a pawl on said bar of sufficient width to engage any one of said arms which has been rendered operative.

66. In a ticket-issuing machine, a ticket-strip-feeding mechanism comprising a reciprocating actuating member, a reciprocating bar arranged parallel to same, a lever or rockable element arranged intermediate said actuating member and engaged with same, a positively-operated driving member pivotally connected to said lever, said driving member being connected to said lever in such a manner that the lever will rock on said actuating member during the first part of the forward stroke of the driving member.

and means under control of the operator for causing said lever to rock on said reciprocating bar at different periods during the last portion of the forward stroke of said 5 driving member so as to cause the actuating member to be moved different distances.

67. A ticket-issuing machine having a ticket-strip-feeding mechanism that comprises a reciprocating actuating member, a 10 movable cutter for severing the ticket strip, a motor-driven element, means operated by said element for positively moving said actuating member and said cutter in both directions, and a plurality of manually-operated controlling devices for limiting the 15 degree of movement of the ticket-strip-feeding mechanism at each cycle of operations of the machine.

68. A ticket-issuing machine having a ticket-strip-feeding mechanism that comprises a reciprocating actuating member, a 20 movable cutter for severing the ticket strip, a motor-driven element, means operated by said element for positively moving said actuating member and said cutter in both directions, a plurality of manually-operated controlling devices for limiting the degree of movement of the ticket-strip-feeding mechanism at each cycle of operations of the machine, a switch for governing the motor that 25 drives said element, and means whereby said switch closes when one of said controlling devices is actuated and opens automatically after the parts of the machine have been 30 restored to starting position.

69. A ticket-issuing machine provided with a ticket-strip-feeding wheel, a star wheel that coöperates with a pawl on said feeding wheel, a reciprocating actuating member for 40 rotating said star wheel forwardly and backwardly, a driving member having a fixed stroke in both directions, a connection between said driving member and actuating member, a plurality of manually-operated 45 controlling stops, and means that coöperates with said stops and with the connection between the driving member and actuating member for governing the degree of movement imparted to said actuating member on 50 the forward stroke of the driving member.

70. A ticket-issuing machine provided with a ticket-strip-feeding wheel, a star wheel that coöperates with a pawl on said feeding wheel, a reciprocating actuating member for 55 rotating said star wheel forwardly and backwardly, a driving member having a fixed stroke in both directions, a connection between said driving member and actuating member, a plurality of manually-operated 60 controlling stops, means that coöperates with said stops and with the connection between the driving member and actuating member for governing the degree of movement imparted to said actuating

member on the forward stroke of the driving member, a movable cutter for severing the ticket strip, a rock arm for actuating said cutter, means for positively moving said rock arm in both directions, a restoring mechanism for said controlling stops, and an 65 operating element for said restoring mechanism that rotates with said star wheel.

71. A ticket-issuing machine comprising a ticket-strip-feed wheel, a reciprocating actuating member, means coöperating with 70 said actuating member for transmitting forward movement to said feed wheel, a plurality of key levers provided with depending arms of different lengths that normally lie side by side in the same vertical plane, a 75 positively operated driving means for said actuating member comprising a reciprocating bar which travels in a path adjacent the depending arms on said key levers, and a pawl on said bar that is adapted to coöperate with 80 the arm on a key lever that has been actuated.

72. A ticket-issuing machine comprising a ticket-strip-feed wheel, a reciprocating actuating member, means coöperating with 85 said actuating member for transmitting forward movement to said feed wheel, a plurality of key levers provided with depending arms of different lengths that normally lie side by side in the same vertical plane, a 90 positively-operated driving means for said actuating member comprising a reciprocating bar which travels in a path adjacent the depending arms on said key levers, a device on said bar that is adapted to coöperate with the arm on a key lever that has been 95 actuated, a movable cutter for severing the ticket-strip, means for positively opening and closing said cutters, and means for positively restoring said key levers to their normal elevated position.

73. A ticket-issuing machine comprising a ticket-strip-feed wheel, a reciprocating actuating member, means coöperating with 100 said actuating member for transmitting forward movement to said feed wheel, a plurality of key levers provided with depending arms of different lengths that normally lie side by side in the same vertical plane, a 105 positively operated driving means for said actuating member comprising a reciprocating bar which travels in a path adjacent the depending arms on said key levers, a pawl on said bar that is adapted to coöperate with the arm on a key lever that has been actuated, a movable cutter for severing the 110 ticket-strip, means for positively opening and closing said cutters, means for positively restoring said key levers to their normal elevated position, a stop for positively arresting the forward movement of the feed 115 wheel, and means for rendering said stop inoperative when the elements of the machine are being restored to starting position,

74. A ticket-issuing machine comprising a top plate, a pair of parallel side plates arranged underneath same, a housing that projects laterally from one of said side plates, a ticket-strip-feeding wheel in said housing, a movable cutter arranged underneath the top plate for severing the ticket strip, and a positively-acting driving means arranged between the two side plates of the machine in a different vertical plane than the feed wheel for moving the various elements of the machine forwardly and also backwardly to restore them to starting position.

75. A ticket-issuing machine comprising a top plate, a pair of parallel side plates arranged underneath same, a housing that projects laterally from one of said side plates, a ticket-strip-feeding wheel in said housing, a movable cutter arranged underneath the top plate for severing the ticket-strip, an actuating mechanism arranged between the two side plates of the machine and comprising a fixed-stroke driving member, a variable-stroke driven member, and a connecting element interposed between said members for transmitting movement from the driving member to the driven member, a support on one of said side plates for sustaining a ticket-strip that has been folded back and forth so as to form a plurality of superimposed portions which lie under the feed-wheel housing, and an arc-shaped guide

arranged outside of said housing for receiving the ticket strip, one wall of said guide 35 being provided with an elongated slot so as to permit devices on the feeding wheel to engage said ticket strip.

76. A ticket-issuing machine provided with a pair of parallel side plates that 40 inclose the main or principal elements of the machine that actuate the ticket-strip-feeding and severing devices, said elements comprising an actuating member which causes the ticket strip to be fed forwardly when 45 said member moves in one direction, and a driving member for moving said actuating member positively in both directions, a housing projecting laterally from one of said side plates adjacent the upper end of 50 same, a feed wheel in said housing for moving the ticket-strip forwardly, a stationary bracket on one of the side plates arranged underneath said housing in vertical alignment with same for holding a box in which 55 a folded ticket strip is arranged, and a means for retaining said box on said support.

In testimony whereof I hereunto affix my signature in the presence of two witnesses, 60 this twenty-fourth day of October, 1914.

WILLIAM L. SULLIVAN.
